UNITED STATES PATENT OFFICE.

JOHN BUTENSCHON, OF ANNISTON, ALABAMA.

ILLUMINATED SIGN.

1,133,926.

Specification of Letters Patent. Patented Mar. 30, 1915.

Application filed May 19, 1914. Serial No. 839,624.

To all whom it may concern:

Be it known that I, JOHN BUTENSCHON, a citizen of the United States, residing at Anniston, in the State of Alabama, have invented new and useful Improvements in Illuminated Signs, of which the following is a specification.

This invention relates to improvements in illuminated signs and has particular application to a double faced sign.

In carrying out the present invention, it is my purpose to provide an illuminated sign which will embody, among other features, a face plate cut out to form the letters or characters and a reflecting plane disposed behind the face plate and arranged diagonally relatively thereto, a source of light being interposed between the spaced edge of the reflecting plane and the adjacent portion of the face plate and projecting its rays onto the reflecting plane so that the light will be projected through the letters or characters of the sign to illuminate the same.

It is also my purpose to provide a double faced illuminated sign which will embody two face plates spaced apart in parallelism and each cut out to form the characters or letters of the sign, and screens placed in face to face contact and disposed immediately behind each face plate, a foraminous reflecting plane being interposed between the rear side of the sets of screens and arranged diagonally thereto, the construction and arrangement being such that the screen behind each face plate forms a background for the other face plate and render the reflecting plane and sources of light within the casing of the sign invisible.

A further object of my invention is to provide a double faced sign wherein the light rays will be conveniently distributed through the face plates of the sign and the characters or letters brought out clearly and distinctly.

With the above and other objects in view, the invention consists in the construction, combination and arrangement of parts hereinafter set forth in and falling within the scope of the claims.

In the accompanying drawings: Figure 1 is a face view of a sign constructed in accordance with the present invention. Fig. 2 is a longitudinal horizontal sectional view therethrough on line 2—2 of Fig. 1. Fig. 3 is a transverse sectional view therethrough on line 3—3 of Fig. 1. Fig. 4 is an enlarged

plan view showing one set of screens placed in face to face contact. Fig. 5 is a longitudinal horizontal sectional view showing a modified form of sign.

Referring now to the drawings in detail, 1 designates a substantially rectangular frame constructed of any suitable material, while 2, 2 indicate face plates closing the opposite sides of the frame and suitably fastened thereto. In the present instance, each face plate 2 is cut out to form a series of circular openings 3 arranged to simulate letters or characters and formed integral with the wall of each opening at the topmost point thereof and extending downwardly and outwardly therefrom is a tongue 4 having the outer surface thereof highly polished, the tongues acting to ornament the characters or letters of the sign.

Disposed immediately behind each face plate 2 and in face to face contact therewith is a screen 5 having the edges thereof suitably secured to the inner walls of the frame and the cross wires arranged diagonally of the face plate, while placed in face to face contact with the screen 5 is a second screen 6 disposed behind the first screen and having the cross wires thereof extending horizontally and vertically, the edges of the screen 6 being appropriately fastened to the inner walls of the frame.

Disposed within the frame 1 between the confronting surfaces of the rear screens 6 and secured to the top and bottom walls of the frame in some suitable manner is a vertical reflecting plane 7 arranged diagonally with respect to the face plates. This reflecting plane is preferably composed of foraminous material, such as wire screen, coated with white enamel.

Secured to each end wall of the frame 1 and projecting into the space between one screen 6 and the spaced end of the reflecting plane are incandescent lamps 8 equipped with reflectors 9 whereby the light rays are projected onto the adjacent face of the reflecting plane 7 and over the face of the reflecting plane the light rays are directed outwardly of the confronting sign through the screens 5 and 6 and openings 3 thereby illuminating the characters or letters of the sign.

In practice, each face of the reflecting plane 7 projects the light rays through the confronting screens 5 and 6 and the sign, while the foraminous material of the reflect-

ing plane and the screens 5 and 6 of one sign form a background for the other sign, the screens 5 and 6 of the particular sign acting to break up the light rays and render the reflecting plane and lamps within the casing invisible.

Extending across the top of the casing and suitably fastened to the upper wall thereof is a concaved reflector 10 preferably composed of aluminum and acting to project the rays of light through the characters or letters in a downward direction in order to illuminate the vicinity of the sign. Secured to the opposite faces of the sign adjacent to the upper edge thereof and projecting outwardly therefrom are lamps 11 which, when illuminated, throw the light rays onto the tongues 4 with the effect to increase the ornamental appearance of the characters of the sign.

In the modified form of the invention illustrated in Fig. 5, two reflecting planes 12 and 13 are employed in place of the single plane 7 and such planes are placed in edge to edge contact and arranged diagonally within the frame, the lamps for illuminating one face of the sign being secured to the opposite end walls of the frame, while those for illuminating the other face of the sign are disposed approximately centrally of such face within the casing formed by the frame and face plates.

From the foregoing description taken in connection with the accompanying drawings, the construction of my improved sign will be readily apparent.

It will be seen that I have provided an illuminated sign wherein the letters or characters are brought out clearly and distinctly and wherein the light rays are projected

through the opposite faces of the sign by means of a single reflecting plane.

While I have herein shown and described certain preferred forms of my invention by way of illustration, I wish it to be understood that I do not limit or confine myself to the precise details of construction herein described and delineated, as modification and variation may be made within the scope of the claims without departing from the spirit of the invention.

I claim:

1. In an illuminated sign, a frame, face plates secured to the opposite sides of the frame and each cut out to form the characters of the sign, a screen disposed at the rear of each face plate and in face to face contact therewith, a second screen in face to face contact with each of said first screens, a reflecting plate composed of foraminous material coated with white enamel interposed between the confronting faces of said last screens and arranged diagonally within the casing and sources of light carried by the opposite end walls of said casing and designed to project their rays onto the adjacent surfaces of the reflecting plate.

2. A face plate for illuminated signs having openings formed therein arranged to simulate characters, tongues formed integral with the walls of the openings at the topmost point thereof, and projected outwardly and downwardly therefrom whereby the face plate of the sign is ornamented.

In testimony whereof I affix my signature in presence of two witnesses.

JOHN BUTENSCHON.

Witnesses:

W. P. ACKER,

LOUISA NONNENMACHER.
